SUNSHADE AND EYESHIELD FOR
HEADGEARMax Bigler, New York, N. Y., assignor to View-
master Corp., New York, N. Y., a corporation
of New York

Application December 15, 1950, Serial No. 201,053

1 Claim. (Cl. 2—10)

1

My invention relates to means for attaching an eye shield to the vizor or peak of a cap or the like.

One object is to reinforce the eye-shield.

Another object is to provide means for adjustably hinging an eye-shield to the under side of the vizor of a cap.

Another object is to provide a hinge construction which permits the eye-shield to be folded flat against the vizor or flat against the crown of the cap.

Another object is to provide means whereby the eye-shield may be readily moved to operative or inoperative position.

Another object is to provide a construction in which the eye-shield can be easily attached or detached and yet which normally holds the eye-shield securely attached.

Another object is to provide an attachment which can be readily made and at low cost.

In its simple and preferred form the invention employs a form of hinge construction consisting of two coacting U-shaped spring clips one of which is attached to the vizor and the other is riveted to the frame of the eye-shield as shown in the accompanying drawing.

Fig. 1 is a side view of a cap with a vizor and eye-shield attached according to my invention, the shield being shown in full lines in its shielding position and shown in its folded positions in dotted lines.

Fig. 2 is a view of the under side of the combination, with the shield folded beneath the edge of the vizor of the cap.

Fig. 3 is a similar view but with the shield folded beneath the edge of the crown.

Fig. 4 is a side view of one of the anchor clips and showing a fragment of the vizor to which it is attached in section and on a greatly enlarged scale.

Fig. 5 is a side view of a hanger and showing in section a fragment of the eye-shield to which it is secured.

Fig. 6 is a side view of connected clips as attached to a section of the vizor.

Fig. 7 is a view of the under side of the connected clips as attached to a fragment of the vizor and shield.

Fig. 8 is a sectional view taken on the plane of line 8—8 of Fig. 7.

The body or crown 1 of the cap may be of any suitable material and shape. Usually it will be formed of flexible material which can be crushed or folded for storage. The vizor 2 may be of any suitable shape and of relatively stiff but flexible

2

material. The eye-shield 3 is formed of a body 4 of transparent material, clear, tinted yellow, green or otherwise and surrounded by a frame 5 of plastic material.

The eye-shield is connected to the vizor by two hinges, each of which has a U-shaped clip 6 secured to the vizor and a complementary hanger clip 7 secured to the eye-shield.

The clip 6 has a base 8 and two projecting spring jaws 9, 9 spaced apart. This clip is secured to the vizor by an eyelet or a tubular rivet 10. Each jaw has a central hole or recess 11.

The other clip 7 has an arm 12, one end of which is riveted to the eye-shield 3 by a tubular rivet or eyelet 13 which passes through a hole 14 in the eye-shield. The frame 5 is clamped between the eyelet head 15 and the finger portion 16 extending perpendicularly from the hanger arm 12 and abutting the frame 5.

It will be noted that the eyelet head 15 is not parallel to the foot 15A thereof but converges theretowards and inwardly of the shield 3 from clamping engagement of the frame 5 and arm 12 to clamping engagement of the arm and body 4 only as best shown in Figure 5. The shield 3 is thus wedged in the eyelet 13 against any accidental pull as well as having its body 4 pierced by the tubular portion of the eyelet and having its inner border portions confined by the fingers 16.

The other end of the arm 12 has two spring flanges 17, 17 spaced apart and provided with semi-spherical bosses 18, 18 adapted to be sprung between the jaws 9, 9, of clips 6 and which fit rotatably in the holes 11 in the jaws for hinging the eye-shield to the vizor. The corners 19 of the flanges 17 are set inwardly a little so as to facilitate insertion of the hanger flanges between the jaws of clip 6.

It will be noted that clips 6 are rotatable under pressure on the vizor so as to adjust them to accommodate the flanges of the hanger clips 7.

The eye-shield is preferably formed of one-piece of flexible sheet plastic material reinforced by the frame. This frame is U-shaped in cross section and is formed of a strip of plastic softened so that it may be applied around the periphery of the shield and cemented in place with the marginal portion of the body 4 firmly engaged in the bight of the U. The ends 20 of the strip are held together and substantially concealed by the head of one of the eyelets of one of the hangers as shown in Fig. 7.

I claim:

In an eyeshield for attachment to the vizor of a hat, the combination with a body of sheet ma-

terial, and a frame of U cross section extending peripherally of said body and firmly connected thereto with the marginal portion of said body engaged in the bight of the U, of means for mounting said shield on said visor, said means comprising a clip, said clip comprising connecting means for engagement with said visor, said clip further comprising an elongated arm, and an eyelet extending through said arm and through said body, said eyelet comprising head and foot portions clampingly engaging said arm and said body, said head portion being nonparallel with said foot portion and converging theretoward in-

wardly of said body, said head portion further clampingly and wedgingly engaging said frame at the inner margin of said frame.
